UNITED STATES PATENT OFFICE

GOTTFRIED STRAUB, OF DEVENTER, NETHERLANDS

CARPET AND METHOD OF MANUFACTURING THE SAME

Application filed October 3, 1928, Serial No. 310,108, and in the Netherlands November 18, 1927.

The known double-woven carpets, such for instance as the so-called ingrain carpets, or chenille-carpets and "Tapis Belges", have the advantage that they are reversible and 5 may be used on both sides.

They have a serious drawback, however, in that both ends of the carpet must be hemmed to prevent the carpet from raveling. The said hem or seam not only disfigures the carpet but also causes the carpet to curl up, so 10 that an obstruction is formed which may cause stumbling in actual use. When using the carpet with the reverse side turned upwards, this obstruction is still greater.

15 The object of the invention is to overcome this drawback and to supply a carpet which, if desired, may be used on the reverse side without any danger of stumbling. Moreover it is not visible whether the right or the reverse side is turned upwards.

According to the invention, a carpet is divided at both ends into an upper and a lower fabric, which fabrics are each folded over inwardly upon themselves and are fastened 25 together. The carpet may be a single, or two-ply or multiply carpet.

It has already been proposed to weave a shirt or collar fabric with tubular portions, which may be cut in the form of sheets or 30 strips of cloth with split ends; or the fabric may be woven with split ends, each half of which ends may be turned in on itself and the halves of the ends stitched together to form a smooth hem on both sides of the fabric.

35 No claim, however, is made to such a fabric and the invention relates only to carpets and the manufacture thereof, and has for its purpose to do away with the old-fashioned turned-over carpet seam.

40 The invention represents an important advance in the carpet-industry, as it is now possible to have a fabric, the two sides of which may be used with equal convenience, at the same time effecting a considerable saving in the costs of floor-coverings. The same applies to one-sided-patterned carpets, so 45 that the said carpets also may be used on the reverse side, which has no turned-over seam.

50 The manufacture of a carpet according to the invention may be carried out in existing

looms, for instance in a jacquard-machine; while the controlling of the shuttles and the ground-binding may be carried out by hand, automatically or semi-automatically.

The invention further contemplates the 55 production of a carpet that may be woven at both ends as an upper and lower fabric, the parts thus obtained being each separately folded over inwardly and fastened together so as to form one piece.

60 Preferably, according to the invention, the portion of the upper and lower fabric ends to be folded over inwardly, is woven with a thinner weft than the adjacent main portion of the carpet.

65 Also, the separate upper and lower fabric ends of the carpet are woven with a thinner weft over their entire length.

An embodiment of the invention will now 70 be described with reference to the accompanying drawings, in which:

Figure 1 is a diagrammatical longitudinal section of the end of a carpet according to the invention.

Fig. 2 is a corresponding section of this 75 carpet and in finished condition.

Fig. 3 is a longitudinal section of a portion of a carpet-strip.

Fig. 4 is a side elevation of a shaft with 80 roller-chain to be mounted at the left hand portion of a carpet loom for controlling the dobbies and the shuttle change for weaving a carpet according to the invention in a drop box dobby loom.

Fig. 5 is a corresponding side-elevation and 85

Fig. 6 is a development of the roller-chain shown in Fig. 4 for the dividing of the carpet into upper fabric.

In Fig. 1 the double warp is indicated by 90 the numerals 1, 2 through which weft threads 3 have been picked in a dobby loom or a "jacquard-machine". At 4 the fabric is divided into an upper and lower fabric having a warp 1 and 2, respectively, and thinner weft threads 5; at 6 still thinner weft threads 7 of smooth yarn or other materials, which later on are hidden from sight, are picked through the upper and lower warp, respectively. At 8 the fabric is cut to size. In the 95 construction of carpet shown in Fig. 3, two 100

pieces of carpet have been woven together end to end.

The fabric cut to size is folded-over along the lines 6, so that the thinner woven ends composed of threads 7 will be disposed at the inside between the upper and lower fabric. The whole is sewn at 9 and, if desired, further finished by being pressed, for example. The total thickness of the seam thus obtained 10 need not be larger than the normal thickness of the main portion of the carpet. The portion of the carpet between the lines 4 may be woven entirely split, i. e. hollow or tubular.

The weaving of the carpet fabric as will 15 be readily understood is different in the split portions than in the body portions of the carpet and it would normally be necessary either to employ a very long pattern chain for controlling the dobbies and shuttles, respectively, or else to change these chains when weaving the two respective parts of the carpets referred to.

Figs. 4, 5 and 6 illustrate a method of controlling the weaving of a carpet according to 20 the invention in a drop box dobby loom. The weaving is controlled by the rotation of roller chains 17 and 20, carried by sprocket wheel sleeves 11 and 12 mounted on a shaft 10 (see Fig. 4). Each chain comprises two sets of 25 rollers, one chain comprising sets 18 and 19, respectively, for controlling the shedding and the other comprising two sets of rollers 21 and 22, respectively, for controlling the shuttle change; and the chains are arranged so 30 that the sets of rollers 18 and 21 or 19 and 22, are operative together to control the weaving. A part of chain 17 is shown fully developed in Fig. 6. The large rollers 18 and 19 cause the lifting of the corresponding 35 warp threads, while the thinner rollers bring about the lowering of the corresponding warp threads.

The sets of rollers 18 and 21 control the weaving during the making of say the body 40 of a carpet, while the sets 19 and 22 control the weaving of the split portions of the carpet; the change of control being effected when the fabric reaches the point represented at 4, 4 in Fig. 3, by sliding the sprocket sleeves 45 carrying the chains to the right or to the left, to bring the appropriate sets of rollers into operative position and to move the other sets out of operative position. The sleeves 11 and 50 12 may be permanently positioned on the shaft 10, which shaft may be slidable; or the sleeves may be slidable on the shaft and secured in position temporarily by means of pins passing through holes 13 or 15 and 14 or 16, respectively, in the shaft, there being 55 a corresponding hole in each sleeve. The holes 13 and 15, and 14 and 16, are disposed so that when the securing pins are passed through them to hold the sprocket in position, the required disposition of the roller

chains is obtained. The manipulation of the chains is thus simplified, as the change of the weaving control can be effected merely by removing the two pins and sliding the sleeves axially and reinserting the pins to 70 maintain the new positioning of the sleeves.

If desired, the sleeves 11 and 12 could be integral or rigidly connected to slide together, or the movement of the sleeves can be effected by a single movement of the shaft 75 10, as has already been mentioned. The shedding may be carried out by the "jacquard-mechanism", thus doing away with the dobbies and the sets of rollers thereon. Other obvious equivalent arrangements might also be suggested, but those above indicated are thought to be the most convenient.

For a good comprehension of the matter it is remarked that the method and device described for the manufacture of a carpet according to the invention are submitted by way of example, since the purpose aimed at may be obtained in various other ways. The operation of the shuttles and shafts, for instance, might be effected entirely by a single 90 "jacquard-mechanism".

I claim:

1. A reversible carpet formed with a double ground warp, said warp being divided at its end portions into two separate ground warps, and said warps being woven with weft threads which are thinner than the weft threads of the main portion of the carpet and separately folded inwardly upon themselves and fastened together so as to form one single piece.

2. A reversible carpet formed with a double ground warp, said warp being divided at its end portions into two separate ground warps, and said warps, together with the weft threads interlaced therewith, being separately folded inwardly upon themselves and fastened together so as to form one single piece.

In testimony whereof I affix my signature.

GOTTFRIED STRAUB.
